VELOCIPED FRAME CONSTRUCTION

Theodore Moll, Fairview Park, Ohio

Application August 2, 1957, Serial No. 675,991

4 Claims. (Cl. 280—282)

The invention relates in general to a velocipede construction and more particularly to a method for constructing a sturdy and safe frame structure which is adapted to maintain the components of a velocipede in their proper position.

An object of the invention is to provide an improved frame structure for a velocipede.

Another object of the invention is to provide a method of holding and making a bearing support member for a velocipede construction.

Another object of the invention is to provide a new and novel bearing support construction for a velocipede.

Another object of the invention is to provide a new and novel construction for supporting the seat structure of a velocipede.

Other objects and a fuller understanding of this invention may be had by referring to the following description and claims, taken in conjunction with the accompanying drawings, in which:

Figure 1 is a perspective view of a velocipede utilizing the improved frame structure of the present invention;

Figure 2 is a plan view of one of the two metal blanks utilized in making the frame structure of the present invention;

Figure 3 is a plan view of the metal blank of Figure 2 after a drawing or forming operation has been conducted thereon;

Figure 4 is a view taken along line 4—4 of Figure 3;

Figure 5 is a plan view of the formed blank of Figure 3 after the flanges thereof have been subjected to a trimming operation;

Figure 6 is a plan view of the trimmed metal blank of Figure 5 after it has been subjected to a flanging and embossing operation;

Figure 7 is a view taken along line 7—7 of Figure 6;

Figure 8 is a plan view of two completely formed complementary metal blanks secured together by means of spot welding to form the frame structure of the present invention;

Figure 9 is a view taken along line 9—9 of Figure 8;

Figure 10 is a plan view of the seat supporting bearing structure utilized in the frame structure of the present invention;

Figure 11 is a view taken along line 11—11 of Figure 10;

Figure 12 is a view taken along line 12—12 of Figure 10;

Figure 13 is a view partially in section of an axle bearing member utilized in the present invention;

Figure 14 is a view taken along line 14—14 of Figure 8; and

Figure 15 is a view taken along line 15—15 of Figure 8.

Figure 1 illustrates a velocipede 20 which includes the frame structure 22 of the present invention which is adapted to secure and support the component parts of the velocipede in their proper positions. Associated with the frame structure 22 of the velocipede is the main

2

front wheel assembly 24, the steering handles 25, a seat 26, and a rear wheel assembly 27.

The frame structure for the velocipede to which the present invention relates and which is best seen in its completed and assembled condition in Figures 1, 8 and 9 has an axis of symmetry which is indicated by the dot-dash line 30. This frame structure comprises first and second hollow mating sections 33 and 34, respectively, each of which has first and second end portions 36 and 37, respectively, and an intermediate portion 38 therebetween. Each of the first and second hollow mating sections has an upper and a lower edge portion 41 and 42, respectively. The lower edge portion 42 of each of the sections is provided with a flange 44 which lies substantially in the same plane as the axis 30 and which extends from the first to the second end portions 36 and 37, respectively. The upper edge portion 41 of each of the sections has a flange 45 on the first end portion thereof and also has flanges 48 and 49 on the intermediate portion. The flanges 45, 48 and 49 lies substantially in the same plane as does the flange 44. The upper edge portion 41 of the first mating section 33 is also provided with first and second flange portions 46 and 47, respectively. These flange portions extend generally normal to the flanges 48 and 49 at the intermediate portion with the first flange portion located at the first end portion of the frame structure and with the second flange located at the second end portion of the frame structure. The upper edge portion 41 of the second mating section 34 is provided with first and second depressed portions 50 and 51, respectively, which are located at the first and second end portions, respectively, of the frame structure and which complementarily interfit with the first and second flange portions 46 and 47 of the first mating section. Each of the mating sections is provided with a half round bearing member support 54 at both the upper and lower edge portions thereof which is located at the first end portion 36 of the frame structure.

Figure 4 is a view taken along line 4—4 of Figure 3; Figure 5 is a plan view of the formed blank of Figure 3 after the flanges thereof have been subjected to a trimming operation; Figure 6 is a plan view of the trimmed metal blank of Figure 5 after it has been subjected to a flanging and embossing operation; Figure 7 is a view taken along line 7—7 of Figure 6; Figure 8 is a plan view of two completely formed complementary metal blanks secured together by means of spot welding to form the frame structure of the present invention; Figure 9 is a view taken along line 9—9 of Figure 8; Figure 10 is a plan view of the seat supporting bearing structure utilized in the frame structure of the present invention; Figure 11 is a view taken along line 11—11 of Figure 10; Figure 12 is a view taken along line 12—12 of Figure 10; Figure 13 is a view partially in section of an axle bearing member utilized in the present invention; Figure 14 is a view taken along line 14—14 of Figure 8; and Figure 15 is a view taken along line 15—15 of Figure 8.

A cylindrical bearing member 57 resides within the half round bearing member supports 54 of the two mating sections and is fixedly secured thereto by spot welding, as at 58. The cylindrical bearing member 57 is best seen in Figure 13 and, as shown, includes wall means which define a cylindrical bearing having first and second spaced end portions. This bearing member 57 is adapted to house the axle which extends from the main front wheel assembly 24 which, in turn, interconnects with the steering handles 25. This bearing member permits turning of the front wheel assembly.

Each of the mating sections 33 and 34 at the intermediate portion thereof has the flanges on the upper and lower edge portions outwardly enlarged, as at 60 (Figure 9), thereby forming a mounting cradle which is adapted to house and hold a seat supporting bearing structure 62 which receives the shaft which extends from the seat 26 to hold the same in place and to provide vertical adjustment therefor. The seat supporting bearing structure 62 is shown in detail in Figures 10, 11 and 12, and includes first and second complementary sections 65 and 66, respectively. Each of the complementary sections 65 and 66 comprises first and second connecting portions 68 and 69, respectively, which terminate at either end portion in spaced mounting ears 70. A half rounded portion 72 is integrally formed with and interconnects the first and second connecting portions 68 and 69, respectively. The first and second complementary sections 65 and 66 are secured together by spot welding as indicated at 75 to form the seat supporting bearing structure. Secured to the inner wall of the first complementary section 65 is a plate 74 and through this plate and section is provided a threaded opening 76 which extends generally normal

to the extent of the connecting portions 68 and 69. A screw 78 threadably interfits the opening 76 to securely hold the shaft which extends from the seat 26 through the opening formed by the bearing structure 62. This screw 78 may be loosened and tightened as desired to provide the proper vertical adjustment to the seat 26. The seat supporting bearing structure 62, shown in Figures 10 through 12, is placed within the mounting cradle formed by the enlarged portions 60 in the two hollow mating sections and is securely spot welded in place, as at 79, best seen in Figure 8. As seen in Figures 8 and 9, the first and second hollow mating sections 33 and 34 are securely held in place by spot welding of the flanges 44, 45, 48 and 49, as indicated generally by the reference numeral 81.

At the second end portion of the frame structure there extends a rear wheel assembly connecting structure 83. This connecting structure 83 is formed as a laterally extending continuation of the mating sections 33 and 34, respectively. This connecting structure includes an annular extending flange 84 which, in the finished velocipede, is connected to the rear wheel assembly 27 by means of spot welding, not shown.

The method of making the frame structure, shown in Figures 1, 8 and 9 includes the steps of selecting first and second metal blanks. One of these metal blanks has been shown in Figure 2 and has been indicated by the reference numeral 88. The metal blanks 88 have first and second end portions 89 and 90, respectively, and an intermediate portion 91 therebetween. The blanks 88 are provided with opposed slots 92 on opposed edge portions 93. These slots 92 are located at the intermediate portion 91 of the blank. Midway between the slots 92, the intermediate portion of the blank is provided with an aperture 94. The next step in making the frame structure of the present invention is the forming of the blanks of Figure 2 into a half shell configuration 97, as shown in Figure 3 and Figure 4, with the flange 98 extending substantially completely around the edge portions of the configuration. This operation is accomplished by the use of male and female dies and may be referred to as a forming or drawing operation. It will be noted in Figure 3 that the width of the flange 98 is substantially the same dimension as the length of the slots 92. In this same forming operation each of the blanks is provided with half round bearing member supports 99 and the nose or first end portion is provided with a rib 100.

The next step is that of trimming the flanges on the half shell configuration shown in Figures 3 and 4 so that they are of consistent dimension throughout their entire length. This trimming operation removes that portion of the flange 98 immediately next to the half round bearing member supports 99 to clearly define the same and at the same time forms the first and second flange portions 46 and 47, respectively, which are the flange portions referred to hereinabove in the discussion of the finished frame structure. At the same time that the first and second flange portions 46 and 47 are being formed the flanges 44, 45, 48 and 49 of the finished frame structure are being formed. This is the step in the construction of the first hollow mating section 33 of the completed frame structure and the construction of the second hollow mating section 34 is identical with the exception that instead of the first and second flange portions 46 and 47 being formed, the metal which makes up these flange portions on the first mating section 33 is completely removed on the second mating section 34. Otherwise the construction of the two is identical so that the two may be assembled to form the completed frame structure of Figures 1, 8 and 9. The next step involved in making the first hollow mating section 33 is illustrated in Figures 6 and 7. This step includes the bending of the first and second flange portions 46 and 47 through an angle of substantially ninety degrees so that they are substantially normal to the flanges 48 and 49. In this

same operation, the rear wheel connecting structure 83 is provided with the annular extending flange 84 and the intermediate portion of the mating sections immediately on either side of the slots 92 is provided with the outwardly enlarged portions 60 which form the mounting cradle for the seat supporting bearing structure 62. The construction of the second hollow mating section 34 is identical with that shown in Figures 6 and 7 for the first hollow mating section 33 with the exception that, instead of bending the flange portions 46 and 47, the second mating section 34 is provided with the first and second depressed portions 50 and 51, shown in Figures 9, 14 and 15. The operation shown in Figures 6 and 7 and described hereinabove is carried out with the use of male and female dies in much the same manner as the operations shown in Figures 3, 4 and 5.

After the first and second hollow mating sections 33 and 34 have been formed, as described hereinabove, they are placed in complementary engagement with each other with the seat supporting bearing structure shown in Figures 10 through 12 in place, and the first flange portion 46 and the first depressed portion 50 are spot welded together immediately behind the bearing member supports 54. This is done without bearing member 57 in place and therefore one of the electrodes of the spot welding apparatus may be inserted through the opening formed by the supports 54 to reach the point of the weld. The cylindrical bearing member 57 is then placed in the position shown in Figure 8 and 9 and is spot welded in place along with the seat supporting bearing structure and the flanges 44, 45, 48 and 49, respectively. The second flange and depressed portions are capable of being spot welded together since the place of weld may be reached through the opening formed by flange 84. The portion of the support structure formed by the first and second flange portions provides a smooth construction which obviates the possibility of injury to a youngster using the velocipede.

After the frame structure 22, shown in Figures 8 and 9, has been completely assembled, the components of the velocipede are assembled, as shown in Figure 1. The axle of the front wheel assembly 24 extends through the cylindrical bearing member 57 and is secured to the steering handles 25 and the bearing member for the seat 26 extends through the seat supporting bearing structure 62 and is held in place and vertically adjusted by means of the screw 78. The annular extending flange 84 of the rear wheel connecting structure 83 is next spot welded in place to the rear wheel assembly 27 and the velocipede is then ready for use.

Although this invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. A frame structure for a velocipede having a vertical plane of symmetry and comprising first and second hollow mating sections, each said first and second hollow mating section having first and second end portions and an intermediate portion therebetween, each said first and second hollow mating section having upper and lower edge portions, said lower edge portion of each said mating section having a flange lying substantially in said plane and extending from said first to said second end portions, said upper edge portion of each said mating section having a flange at said first end portion and at said intermediate portion and lying substantially in said plane, said upper edge portion of said first mating section having first and second flange portions extending generally normal to said flange at said intermediate portion and located at said first and second end portions,

said upper edge portion of said second mating section having first and second depressed portions at said first and second end portions and being complementary to said first and second flange portions of said first mating section, each said mating section having a half round bearing member support at the upper and lower edge portion thereof and located at said first end portion, a cylindrical bearing member residing within said bearing member supports and being spot welded thereto, each said mating section having an outwardly enlarged portion at the upper and lower edge portion thereof forming a mounting cradle and located at said intermediate portion, a seat supporting bearing structure including first and second complementary sections, each said section comprising first and second connecting portions terminating at either end portion in spaced mounting ears, a half rounded portion integrally formed with and interconnecting said first and second connecting portions, said first and second complementary sections being spot welded together, said half rounded portion of one of said complementary sections having a threaded opening extending generally normal to the extent of said connecting portions, screw means in said threaded opening for securing a shaft in place, said seat supporting bearing structure residing in said mounting cradle and being spot welded in place, and spot welding means extending between said flanges for securing said hollow mating sections together.

2. A frame structure for a velocipede comprising first and second hollow mating sections, each said first and second hollow mating section having first and second end portions and an intermediate portion therebetween, each said first and second hollow mating section having upper and lower edge portions, said lower edge portion of each said mating section having a flange extending from said first to said second end portions, said upper edge portion of each said mating section having a flange at said first end portion and at said intermediate portion, said upper edge portion of said first mating section having first and second flange portions extending generally normal to said flange at said intermediate portion and located at said first and second end portions, said upper edge portion of said second mating section having first and second depressed portions at said first and second end portions and being complementary to said first and second flange portions of said first mating section, each said mating section having a half round bearing member support at the upper and lower edge portion thereof and located at said first end portion, a bearing member residing within said bearing member supports and being secured thereto, each said mating section having an outwardly enlarged portion at the upper and lower edge portion thereof forming a mounting cradle and located at said intermediate portion, a seat supporting bearing structure including first and second complementary sections each having mounting ears thereon, said first and second complementary sections being secured together, screw means cooperating with said seat supporting bearing structure

for securing a shaft in place, said seat supporting bearing structure residing in said mounting cradle with means securing same in place, and means extending between said flanges for securing said hollow mating sections together.

3. A seat supporting bearing structure including first and second complementary sections, each said section comprising first and second connecting portions terminating at either end portion in spaced mounting ears, a half rounded portion integrally formed with and interconnecting said first and second connecting portions, said first and second complementary sections being spot welded together, a plate secured to one of said half rounded portions, said one of said half rounded portions having a threaded opening extending through said plate and said half rounded portion and generally normal to the extent of said connecting portions, and screw means in said threaded opening for securing a shaft in place.

4. A frame structure for a velocipede comprising first and second hollow mating sections, each said first and second hollow mating section having first and second end portions and an intermediate portion therebetween, each said first and second hollow mating section having upper and lower edge portions, said lower edge portion of each said mating section having a flange, said upper edge portion of each said mating section having a flange, said flanges of each said mating section being outwardly enlarged thereby forming a mounting cradle at said intermediate portion, a seating supporting bearing structure including first and second complementary sections, each said section comprising first and second connecting portions terminating at either end portion in spaced mounting ears, a half rounded portion integrally formed with and interconnecting said first and second connecting portions, said first and second complementary sections being spot welded together, said half rounded portion of one of said complementary sections having a threaded opening extending generally normal to the extent of said connecting portions, screw means in said threaded opening for securing a shaft in place, said seat supporting bearing structure residing in said mounting cradle and being spot welded in place, and spot welding means extending between said flanges for securing said hollow mating sections together.
